UNITED STATES PATENT OFFICE

162,321

AIRPLANE

Edward M. Lanier, Croydon, Pa.

Application March 28, 1949, Serial No. 1,676

Term of patent 14 years

(Cl. D71—1)

To all whom it may concern:

Be it known that I, Edward M. Lanier, a citizen of the United States of America, residing at Croydon, in the county of Bucks and State of Pennsylvania, have invented a new, original, and ornamental Design for an Airplane, of which the following is a specification, reference being had to the accompanying drawing, forming part thereof.

Fig. 1 is a front view of an airplane embodying my new design with the airplane in level-flight position.

Fig. 2 is a similar view with the airplane in landed position.

Fig. 3 is a top perspective view of the same, the plane being viewed from the rear and above at an angle of about 45°, the plane being viewed in landed position.

Fig. 4 is a perspective view of the airplane from the rear looking up at an angle of about 30°.

Fig. 5 shows the plane in side view in level-flight position.

Fig. 6 is a perspective view of the same looking from right rear side forward, the plane being in landed position.

The present application is a continuation in part of my application filed March 27, 1947, Serial No. D. 137,945, now abandoned.

I claim:

The ornamental design for an airplane, substantially as shown.

EDWARD M. LANIER.
